UNITED STATES PATENT OFFICE.

ARZENO J. DILLEY, OF IONIA, MICHIGAN, ASSIGNOR TO STANLEY VEHICLE SPRING COMPANY, INC., OF SYRACUSE, NEW YORK, A CORPORATION OF NEW YORK.

SELF-LUBRICATING VEHICLE-SPRING.

1,240,322.

Specification of Letters Patent. Patented Sept. 18, 1917.

Application filed September 16, 1915, Serial No. 51,039. Renewed July 9, 1917. Serial No. 179,572.

To all whom it may concern:

Be it known that I, ARZENO J. DILLEY, a citizen of the United States, residing at Ionia, in county of Ionia and State of Michigan, have invented certain new and useful Improvements in Self-Lubricating Vehicle-Springs, of which the following is a specification.

My invention relates to an improvement 10 in self-lubricating vehicle springs, and the object is to provide a dustless self-lubricating leaf spring, the members of which will not stick from friction, but will be sufficiently lubricated at all times to permit freedom of action without unduly catching or accumulating dirt and dust.

With these objects in view, my invention consists of superimposed leaves, having perforated depressions stamped in their outer 20 ends, in connection with a cap approximately fitting the depressions and the holes therein, and inclosing an absorbent disk, which bears upon the leaf below and forms a means of lubricating it.

25 In the accompanying drawings:—

Figure 1 is a view in longitudinal section; Fig. 2 is a view of one of the leaves; and Fig. 3 is an edge view of one of the caps with the absorbent disk separated therefrom.

The numerals 1, 2 and 3 represent the lower, intermediate and upper leaves of my improved self-lubricating spring, all of which are secured together at the center in 35 any approved manner, as for instance by a bolt 4 or similar means.

All but the lowermost leaf preferably have a depression 5 stamped in the outer end thereof, in the center of which is a hole 6.

40 A cap 7 of corresponding shape is adapted to fit each depression, and a button 8 at the center of the cap substantially fits the hole 6. Beneath the cap, a pad or disk of felt or other absorbent material 9 is held in contact with the leaf below.

These springs are of few parts, all of

which are easily made and can be assembled with facility, and in actual tests they have demonstrated their ability to keep the members sufficiently lubricated without being too 50 fluid, thereby wasting lubricant and making the parts greasy, dirty and unsightly; but by this means they are kept clean, free from dust and dirt, while wear and noise due to friction is precluded.

55

It will be seen from the construction described, that the buttons on the caps approximately fill and fit the holes in the depressions, although ample space is left for lubricant, the oil being poured in through 60 the perforations or holes in the depressions, and thence finding its way in the space between the caps and the depressions to the absorbent disk, and thence to the leaf below 65 so that a very few drops in each perforation will keep the leaves amply lubricated, and the springs are kept free of surplus oil.

While I have shown my invention applied to a cantaliver spring, it is perfectly obvious that it is applicable to any leaf-spring.

70

I claim:—

1. A self-lubricating spring comprising leaves secured together, their ends having recesses and caps which approximately fit the recesses, and an absorbent disk interposed between each cap and the adjacent leaf of the spring.

75

2. A self-lubricating spring comprising leaves secured together at the center, their ends having perforated depressions in connection with caps which approximately fit the depressions, said caps each having a button which enters the perforation in the depression, and an absorbent disk interposed between the cap and the adjacent leaf of the 85 spring.

In testimony whereof I affix my signature.

ARZENO J. DILLEY.
